SPINDLE FOR SPINNING AND TWISTING FRAMES

Thomas Harris, Warwick Neck, R. I.

Application May 6, 1950, Serial No. 160,472

4 Claims. (Cl. 308—151)

1

This invention relates to a spindle of the type used in the textile industry in a spinning frame or a twisting frame.

Spindles are usually mounted upon a rail and driven by a tape or belt. Yarn packages are mounted on the upper blade portion of the spindle. In ring spinning or twisting, the spindle must be in proper alignment with the ring. Heretofore, it has been customary in setting the spindle in the box rail to mount the base in the rail in such a position that it was centered with reference to the ring when closest to the rail. Then the ring was moved to a location its greatest distance from the rail and an attempt was made to center the upper part of the blade in the ring by shims between the base and the rail in order that the proper alignment might be secured. This is a slow, tedious and inaccurate method of procedure.

One of the objects of this invention is to provide a means for centering the upper part of the spindle blade in the ring in its position furthest from the box rail by shifting the relative position of the lower bearing in which the blade rotates with reference to the base.

Another object of this invention is to provide an arrangement so that the base has two parts surrounding the lower bearing and these two parts through eccentric relationships may be adjusted for varying the position of the lower bearing of the spindle to provide any desired position.

Another object of the invention is to eliminate the necessity of the use of shims to change the position of the axis of the base with reference to the rail in which it is mounted but rather change the lower bearing for the blade with reference to the upper bearing in the upper portion of the base.

With these and other objects in view, the invention consists of certain novel features of construction, as will be more fully described, and particularly pointed out in the appended claims.

In the accompanying drawings:

Fig. 1 is a central sectional view through the spindle and the rail in which it is mounted and illustrating in dotted lines different positions of the ring with reference to the spindle.

Fig. 2 is a sectional view of the lower section of the base.

Fig. 3 is a sectional view of the sleeve which is located at the lower end of the section of the base.

Fig. 4 is a sectional view on line 4—4 of Fig. 2.

Fig. 5 is a sectional view on line 5—5 of Fig. 3.

Fig. 6 is a sectional view on line 6—6 of Fig. 1, showing the parts of Figs. 4 and 5 in one relative position for mounting the lower spindle blade

bearing midway of its possible position to either side.

Fig. 7 is a sectional view showing the arrangement of the parts in Fig. 6 with a shift for mounting the bearing to one side of the center as shown in Fig. 6.

Fig. 8 is a sectional view of a different position of the parts to position the bearing an extreme on the other side of the center from that shown in Fig. 7.

Fig. 9 is a diagrammatic view illustrating the axial lines of the spindle blade to diagrammatically indicate the result of shifting of the lower bearing for the spindle blade by means of its eccentric mounting.

In proceeding with this invention, I have found a bore in the lower section of the spindle base eccentrically to the axial line through the base and I have provided a sleeve which has an outer cylindrical surface rotatable in the section bore and a cup for mounting the bearing which is also eccentric with reference to this sleeve outer surface. The sleeve may be mounted in the eccentric bore of the lower section of the base so that as the section and sleeve are relatively rotated different positions may be had for the center of the lower blade bearing with reference to the bearing at the upper part of the base in which the blade may fulcrum.

With reference to the drawings, 10 designates the box rail of a spinning or twisting frame in which the spindle is mounted. A ring for a traveler is designated 11 in its lower position and 11' in its upper position with reference to the spindle assembly. This spindle assembly is designated generally 12 and is provided with a base designated 13 which comprises an upper section 14 having a flange 15 forming a shoulder beneath it to rest upon the upper surface of the rail 10 as the section 14 projects through the opening 17 in this rail. This section of the base is threaded as at 18 and is secured in proper position with relation to the opening 17 by a nut 19 engaging a washer 20 between this nut and the lower surface of the rail 10. The base also comprises the lower section 21 which has internal threads 22 to engage the threads 18 and may be rotated on the section 14 through this threaded engagement therewith. This section is held in the desired rotative position by a nut 23 which secures it in such adjusted position as it may be moved to.

A ball bearing 24 is set in a cushion mounting such as rubber 25 in the upper part of the base section 14 and is held in place by a cap 26 having 55 a flange 27 which is threaded to engage threads on

the outer surface of the upper end of the base section 14. This bearing 24 receives a spindle blade 30 which has a lower portion 31 extending into the base 13 through the upper section 14 and into the lower section 21. The upper portion 32 of the blade extends through the ring for the traveler 11, and carries the package, while a whirl 33 is provided on this assembly for rotation of the spindle and package carried thereon by means of a tape or belt.

The lower section 21 of the base has a circular bore 35 which is eccentrically located with reference to the axial line through the base sections 13 and 14 when assembled (see particularly Figs. 2 and 4). A sleeve 36 has a closure 37 and is of an outer cylindrical size 39 to fit the bore 35 for rotation therein. This sleeve has a circular bore 38 which has its center eccentrically located with reference to its outer cylindrical surface 39. This bore 38 is of a size to receive a ball bearing 40 into which the lower end of the blade 31 is stepped. A set screw 41 is rotatably located in a plug 42 extending through the wall of the section 21 so as to engage a groove 43 in the sleeve 36. This set screw 41 will prevent the relative rotation of the sleeve when finally adjusted in the section 21.

In use, the base will be located in the rail 10 so that it will be as near center as possible to the ring 11 when in its lower position and the nut 19 will be set up to hold this base section in place. The ring will then be raised to its uppermost position relative to the spindle, as shown in 11', and the nut 23 will be loosened so that the section 21 may be relatively rotated upon section 14 and the set screw 41 will be loosened so that the sleeve 36 may be relatively rotated on the section 21. By means of the rotation of both section 21 and the sleeve 36 the bearing 40 with the lower end of the spindle blade will be adjusted in such amount as is necessary, the amount possible being shown by the double lines between Figs. 7 and 8 so that the upper end of this spindle will run true with reference to the ring when in the position shown at 11'. This adjustment occurs by the rocking of the spindle blade about the center 45 of the bearing 24 as a pivot (see Fig. 7). The movement about this point 45 as a fulcrum occurs by adjustment of point 46 which represents the lower bearing until the spindle blade axis 47 assumes an alignment at the center of the ring in the upper positions of the spindle. After this has been obtained the nut 23 is screwed down upon the section 21 to maintain it secure with reference to the previously secured section 14 of the base while the set screw 41 is tightened up to maintain the sleeve 36 in its adjusted position relative to the lower section 21 of the base. Thus the alignment of the bearings is secured without the necessity of shims located between the shoulder 16 and the box rail as has heretofore been customary.

The provision of the base in two sections 14 and 21 also provides a construction which will

obtain all of the advantages of my copending application, Ser. No. 118,613, of which this is a continuation in part as well as to enable the advantages above set forth.

5 I claim:

1. A spindle for spinning and twisting frames comprising a base, a spindle blade extending into the base, said base having two sections relatively movable with reference to each other, 10 a bearing for the blade in one of said sections, a sleeve rotatively mounted in the other of said sections, a second bearing for said blade in said sleeve, said second bearing being eccentrically mounted in said sleeve and said sleeve being eccentrically mounted in the said other section.

2. A spindle for spinning and twisting frames comprising a base, a spindle blade extending into the base, said base having two sections relatively movable with reference to each other, 20 a bearing for the blade in the upper of said sections, a sleeve rotatively mounted in the lower of said sections, a second bearing for said blade in said sleeve, said second bearing being eccentrically mounted in said sleeve and said sleeve being eccentrically mounted in the lower section.

3. A spindle for spinning and twisting frames comprising a base, a spindle blade having a portion thereof extending into the base and a portion extending above said base for receiving a package core thereon, a whorl fixed to said blade for rotation of said blade, a bearing for the blade mounted in the upper portion of the base and a second bearing for the blade mounted 35 in the lower portion of the base, a sleeve mounting one of the bearings, said sleeve being eccentrically mounted for rotation in the base.

4. A spindle for spinning and twisting frames comprising a base, a spindle blade having a portion thereof extending into the base and a portion extending above said base for receiving a package core thereon, a whorl fixed to said blade for rotation of said blade, a bearing for the blade mounted in the upper portion of the base and a second bearing for the blade mounted 45 in the lower portion of the base, a sleeve mounting the lower bearing, said sleeve being eccentrically mounted for rotation relative to another portion of the base.

50 THOMAS HARRIS.
